UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

DRILL-SHARPENER.

1,393,403.

Specification of Letters Patent. Patented Oct. 11, 1921.

Application filed April 1, 1920. Serial No. 370,553.

To all whom it may concern:

Be it known that I, WILLIAM A. SMITH, a citizen of the United States, residing at Easton, in the county of Northampton and 5 State of Pennsylvania, have invented a certain new and useful Improvement in Drill-Sharpener, of which the following is a specification.

This invention relates to drill sharpeners, 10 but more particularly to that type of sharpener in which the drill steel is operated upon by fixed and movable dies, the movable die being carried by a reciprocating cross head having a fluid actuated piston or 15 plunger.

In tools of this type the movable parts are heavy and considerable force is necessary in bringing the dies together for the sharpening operations, so that breakage may 20 occur unless provision is made to guard against accidental uncushioned impact of the dies, or too great impact of the reciprocating and stationary parts of the machine on either the up or down stroke.

25 Means have heretofore been provided for cushioning the parts of a sharpener either on the up stroke or the down stroke, but I have devised simple and efficient means for cushioning the reciprocating member on 30 both the up and down strokes so that jar and breakage is prevented under substantially all circumstances.

I have found that the cushioning device should not come into operation too early on 35 either the up or down stroke of the movable member because this tends to slow up the operation of the machine, which should be positive and quick acting in order to enable the operator to sharpen the maximum number of bits in a given time. Accordingly, an object of this invention is to 40 provide cushioning means for both ends of the stroke of the reciprocating member which are positive in operation, but do not 45 slow up the operation of the machine.

A further object of the invention is to 50 secure efficient cushioning of the reciprocating member and its parts in a sharpener of the type in which constant fluid pressure is applied and maintained upon the under side or on the lower end of the shank of the fluid actuated plunger. In such case the cushioning means for the up stroke is particularly desirable in addition to the cushioning of 55 the down stroke.

The invention is illustrated in one of its preferred forms in the accompanying drawing which is a front elevation partly in vertical section of so much of a drill sharpener as will show the invention.

60 Referring to the drawings, A represents the base of a drill sharpener preferably provided with the flange B upon which is mounted the cylinder C. A fluid actuated piston or plunger D is adapted to reciprocate in the cylinder C and one or more plunger rods or posts E carry a cross head F provided with the upper half of the die member or die receiving socket G. The stationary half of the die receiving socket H 70 forming the stationary die member is preferably formed on the anvil block J.

The plunger rod E shown in the drawing, is formed with a stem K provided with the sleeve L forming a shank or extension for 75 the piston D adapted to reciprocate within the reduced cylinder extension O suitably supported within the base A.

80 The admission and distribution of motive fluid pressure to the cylinder C for actuating the piston D is controlled by a suitable valve P conveniently mounted in the valve chest Q at the side of the machine. The valve may be operated by a suitable handle and through the medium of a rack R at one 85 end of the valve.

85 In the type of machine illustrated in the drawings, motive fluid pressure is constantly supplied to the end face of the piston shank or extension K and its surrounding sleeve 90 L through the passage S and inlet T so that the piston D and cross head F carrying the die member G is constantly urged in an upward direction.

95 Motive fluid for actuating the piston D is admitted at the inlet port U of the valve chest and may pass from said inlet port through the passage V above the piston D for the down stroke. The valve is shown in the drawing in exhaust position, closing 100 the inlet to the cylinder. On the up stroke, pressure is exhausted from the cylinder through the valve chest to the exhaust port W. The underside of the piston D is open to atmosphere through the ports X as 105 shown.

110 In accordance with this invention and in order to cushion the down stroke of the piston D, said piston is provided with a recess or pocket at Y on its underside, and the

upper portion of the case A is provided with a projection Z adapted to enter the recess or pocket Y and trap a small amount of air between the piston and the projection 5 Z for cushioning purposes. For cushioning the up stroke of the piston, the cylinder head is provided with the recess or pocket a and the upper surface of the piston D is provided with a projecting portion b adapted to enter the recess or pocket a and trap a small amount of air for cushioning purposes.

10 I have found that in accordance with this construction, the speed of the piston D may be increased without danger of breaking the operative parts of the machine, and I am enabled to cushion the reciprocating parts both on the up stroke and the down stroke without material loss of power, which occurs when the cushioning devices come into 15 operation too early in the stroke.

I claim:

1. A drill sharpener having a stationary die member, a reciprocating die member, a 20 cylinder, a piston therein connected to operate the reciprocating die member, fluid actuating means for said piston, a recess or 25

pocket at the upper end of the cylinder adapted to receive a projecting portion on the 30 piston for cushioning the piston on the up stroke, ports through the lower wall of the cylinder affording communication between the interior of the cylinder and the atmosphere, and means forming part of the piston for closing communication through 35 said ports when the piston approaches the end of its down stroke, whereby air is trapped below the piston to form a cushion.

2. A drill sharpener having a stationary die member, a reciprocating die member, a 40 cylinder, a piston therein connected to operate the reciprocating die member, fluid actuating means for said piston, ports through the lower wall of the cylinder affording communication between the interior of the cylinder and the atmosphere, and means forming part of the piston for closing communication through 45 said ports when the piston approaches the end of its down stroke, whereby air is trapped below the piston to form a cushion.

In testimony whereof, I have hereunto set my hand.

WILLIAM A. SMITH.
